UNITED STATES PATENT OFFICE.

WILLIAM M. STRONG, OF SANTA BARBARA, CALIFORNIA.

DRIER.

Application filed May 3, 1926. Serial No. 106,229.

This invention relates to improvements in the construction of forced circulation kilns or chambers for drying and conditioning lumber, fruit and similar materials.

5 The object of the present invention is to generally improve and simplify the construction and operation of driers; to provide a drier or kiln in which forced air circulation is obtained by a continuously 10 driven, power-operated fan and reversal of the air at predetermined time intervals by a damper control; to provide a kiln or drier in which a maximum volume of air is continuously circulated over and over 15 again and a predetermined humidity content maintained by condensing out excess moisture; to provide a kiln in which the internal air pressure is automatically maintained by means of equalizing air ducts, allowing excess moist air to escape with a corresponding inlet of fresh air; to provide a kiln capable of operation under any desired 20 drying schedule based upon the adjustment and control of heat and humidity, with air 25 as the circulating medium; to provide a kiln in which condensation of moisture when it does occur takes place below the drying chamber; to provide a kiln or drier in which 30 equalized and uniform temperatures may be maintained throughout; and, further, to insure a uniform product by uniform air distribution and by maintaining close humidity 35 and temperature control.

The drier is shown by way of illustration 35 in the accompanying drawings, in which—

Fig. 1 is a central, vertical, longitudinal section through the drier.

Fig. 2 is a plan section, taken on the line 2—2 of Fig. 1.

40 Fig. 3 is an end cross section taken on the line 3—3 of Fig. 1.

Referring to the drawings in detail, A and B indicate a pair of interspaced side walls carried by a floor or base section C. 45 The walls and floor sections are extended to any length desired and are covered by a roof section D, thereby producing a kiln or drier of considerable length when comparison is made with its width and height.

50 Disposed interiorly of the drier is an intermediate floor section 2 and a pair of interspaced walls 3 and 4 which extend from one end to within three or four feet of the front of the other end of the drier. These 55 walls, together with the intermediate floor section, divide the drier into an upper dry-

ing chamber E, a plenum chamber F and a pair of return air passages G and H. All the chambers and passages formed extend from end to end of the drier and their function and purpose will be hereinafter described. A trackway 5 extends through the drying chamber so that the material to be dried may be loaded on trucks and readily transported into and out of the drier. Each 60 end of the drying chamber is, of course, provided with doors, such as shown at 6, which are open and closed as the trucks are moved into or out of the drying chamber.

The walls 3 and 4 forming the plenum 70 chamber and the return air passages G and H extend from one end of the drier, as shown in Fig. 2, to the point indicated at 7. An end passage 8 is thus formed which communicates with the open end of the 75 plenum chamber and with the respective return air passages G and H. A fan or blower 10 is mounted in the open end of the plenum chamber and the fan discharges the air in the direction of the arrow —a— into 80 the plenum chamber. Its suction side is presented to the passage 8 and air may thus be drawn from either of the return passages, as will hereinafter be described.

The fan may be driven in any suitable 85 manner, for instance, by an electric motor, such as indicated at 11, and the air circulated by the fan is alternately heated and cooled when in circulation. Heating coils 12 are mounted in the upper portion of the 90 plenum chamber and they may be heated in any suitable manner, for instance, by the circulation of steam obtained from an exterior boiler or other suitable source of supply. Cooling of the air is ensured when the air 95 passes through the return passages; this being accomplished by the conduction of heat to the side walls A and B by the admission of fresh air through dampers 25 and 26, and may further be assisted by water spray 100 discharging from spray pipes such as shown at 14 and 15. The spray may also serve the purpose of washing out of the circulating air acid vapors from evaporation of the moisture, especially in redwood, preventing 105 to a large extent corrosion of fan blades, housing and other metals within the kiln. Valves, such as indicated at 16, are employed to regulate the flow of cooling water.

Formed in the upper parts of the plenum 110 chamber walls 3 and 4 is a series of interspaced air ducts 17 and 18, and cooperating

with each set of ducts are dampers 19 and 20. The dampers 20 are all mounted on or controlled by one common shaft 21 extending through one side of the kiln and provided with a lever 22 whereby the shaft may be operated. Links 23 connect the dampers 19 and 20 and the connection is such that one set of dampers will assume an open position when the opposite set assumes a closed position. This arrangement is of particular importance as it permits operation of the dampers in unison and, above all, permits reversal of the circulating air as will now be described.

15 In actual operation with the dampers assuming the position shown in Fig. 3, the air entering the plenum chamber and maintained in circulation by means of the fan 10 will discharge through the ducts 18 and it will be deflected upwardly into the drying chamber, as indicated by the arrows. Graftings or walks are arranged on each side of the trackway 5 for the convenience of the workers, and they also serve another function, to-wit, that of evenly distributing the air discharging from the ducts 17.

If the trucks are loaded with lumber, the air will pass laterally through the sticker spaces of the stacks contained on the trucks and will then flow downwardly on the opposite side of the trucks and return through the openings 25 which communicate with the return duct H. The air will then flow longitudinally of this duct in the direction of the arrows and will enter the end chamber 8 and the suction side of the fan 10, to be circulated over and over again. The air, during its passage through the lumber, picks up a certain amount of moisture and this may be in part precipitated out during the passage of the air through the return duct H by conduction of heat to the side walls by water spray action, or by admitting more or less cool air through the dampers 25^a and 26.

The floor section of the return ducts slopes, as shown in Fig. 3, and gutters are formed in the sides to collect and carry away the moisture condensed within the kiln. The principal advantage of this arrangement is to prevent condensation of moisture in any part of the kiln above the track level. The air on entering the plenum chamber is again brought up to the required temperature and it is accordingly alternately heated and cooled during each cycle of recirculation.

By referring to Figs. 1 and 2, it will be noted that the upper dampers 25^a are pivotally mounted in passages 25^b and similarly that the dampers 26 are sliding dampers and as such may be manually open or closed. The humidity content of the air circulating within the kiln as previously stated is controlled by a steam jet 27, and by conduction of heat to the side walls in the bottom of

the kiln. This also is controlled by water spray action in the return ducts G and H, and it is further controlled by admitting fresh cool air from the outside, this air being admitted by regulating the sliding dampers 26.

In actual practice it is found that when the sliding dampers are partially opened air will enter and moist air will at the same time discharge through the upper dampers 25^a. That is, the lower dampers 26 are positioned closer to the suction side of the circulating fan and air is accordingly pulled into the kiln through the suction action of the fan. It is, of course, impossible to maintain an air pressure greater than atmospheric pressure, and as fresh air enters a proportionate volume of moist air must be discharged. This is automatically taken care of by the swinging dampers 25^a, as they are placed a greater distance from the suction side of the fan than the damper 26 and any slight pressure will cause them to swing outwardly and thereby permit a proportionate amount of moist air to discharge.

For edge stacked loading the design may be modified by suitable arrangement of dampers.

During the operation lever 22 is grasped by the operator at suitable time intervals and rocked to reverse the position of the dampers 19 and 20. This reversal of the position of the dampers reverses the flow of air through the drying chamber and the lumber or other material dried is thus subjected to a uniform application of air. Practically any temperature may be maintained by regulating the flow of steam through the heating coils and practically any humidity content may be maintained by opening or closing the humidity steam jet 27.

A tunnel type of drier is in reality employed, but the air flow is not longitudinally thereof as is common practice but conversely the air flow is transversely of the passage or tunnel at all points. It is accordingly impossible for the air to become moisture laden and to precipitate its moisture at points further ahead in the tunnel as is the usual result with ordinary types of tunnel driers. If for any reason it is decided to add moisture content to the circulating air a steam outlet is provided as shown at 27.

The general arrangement is such that a very fast and uniform circulation of air and vapor through the piles of lumber or other material in the process of drying may be secured. The arrangement permits periodic reversal of the direction of air movement by closing the dampers on one side of the plenum chamber and opening the dampers on the opposite side. The arrangement also permits the use of a fan which continuously rotates in one direction. This is of particular importance as a curved blade disk fan

of the mine ventilating type having almost double the efficiency of an ordinary flat blade disk fan and capable of operating against the resistance of one inch static pressure may be employed. The air distributing system provides a very uniform flow of air throughout the length and breadth of the kiln and eliminates non-uniformity of drying which is one of the commonest troubles experienced in the ordinary kiln.

While certain features of the present invention are more or less specifically described and illustrated, I wish it understood that various changes may be resorted to within the scope of the appended claims. Also I wish it understood that the materials and finish of the several parts employed may be changed to suit varying conditions.

Having thus described my invention, what I claim and desire to secure by Letters Patent is—

1. In a dry kiln having an elongated plenum chamber, a pair of return air passages and a superposed drying chamber, a plurality of air ducts on each side of the plenum chamber, and dampers cooperating with said ducts and adapted to place the ducts on opposite sides alternately in communication with the plenum chamber and the return passages.

2. In a dry kiln having an elongated plenum chamber, a pair of return air passages and a superposed drying chamber, a plurality of air ducts on each side of the plenum chamber, dampers cooperating with said ducts and adapted to place the ducts on opposite sides alternately in communication with the plenum chamber and the return passages, and circulating means adapted to maintain a continuous circulation of air through the plenum chamber, the air ducts, the drying chamber and the return passages.

3. In a dry kiln having an elongated plenum chamber, a pair of return air passages and a superposed drying chamber, a plurality of air ducts on each side of the plenum chamber, dampers cooperating with said ducts and adapted to place the ducts on opposite sides alternately in communication with the plenum chamber and the return passages, circulating means adapted to maintain a continuous circulation of air through the plenum chamber, the air ducts, the drying chamber and the return passages, and means for reversing the dampers in unison to reverse the flow of air through the drying chamber.

4. In a dry kiln having an elongated plenum chamber, a pair of return air passages and a superposed drying chamber, a plurality of air ducts on each side of the plenum chamber, dampers cooperating with

said ducts and adapted to place the ducts on opposite sides alternately in communication with the plenum chamber and the return passages, and circulating means adapted to maintain a continuous circulation of air through the plenum chamber, the air ducts, the drying chamber and the return passages, and means for heating the air to a predetermined temperature.

5. In a dry kiln having an elongated plenum chamber, a pair of return air passages and a superposed drying chamber, a plurality of air ducts on each side of the plenum chamber, dampers cooperating with said ducts and adapted to place the ducts on opposite sides alternately in communication with the plenum chamber and the return passages, circulating means adapted to maintain a continuous circulation of air through the plenum chamber, the air ducts, the drying chamber and the return passages, and means for cooling the air during its travel through the return passages to condense moisture below the track level in the kiln.

6. In a dry kiln having an elongated plenum chamber, a pair of return air passages and a superposed drying chamber, a plurality of air ducts on each side of the plenum chamber, dampers cooperating with said ducts and adapted to place the ducts on opposite sides alternately in communication with the plenum chamber and the return passages, an air circulating fan in the plenum chamber, air heating means in the plenum chamber, means for regulating the temperature of said heating means and the air heated thereby, cooling means in the air return passages, and means for regulating the temperature of said cooling means and the air cooled thereby.

7. An apparatus of the character described comprising an elongated housing, a horizontal partition therein dividing the housing into upper and lower compartments, said upper compartment being a drying compartment, a pair of interspaced vertical partition members in the lower compartment forming a central plenum chamber and a pair of exterior air return passages, a plurality of air ducts arranged on each side of the horizontal partition member, dampers in said ducts adapted to place the ducts on one side in communication with the plenum chamber and the ducts on the other side in communication with one of the air passages or vice versa, means for reversing the position of the dampers in unison, and means for maintaining a continuous circulation of air through the plenum chamber, the ducts, the drying chamber and one or another of the return passages.
